TRAY FOR A DRILL PRESS

Frank P. Mikulski, Utica, Mich.

Application September 6, 1957, Serial No. 47,640

Term of patent 3½ years

(Cl. D63—1)

FIG. 1

FIG. 2

FIG. 3

FIG. 4

Fig. 1 is a top plan view of a tray for a drill press showing my new design;

Fig. 2 is a front elevational view thereof;

Fig. 3 is a side elevational view thereof; and

Fig. 4 is a fragmentary section on the line 4—4 of Fig. 1. The bottom of the article is substantially plain.

I claim:

The ornamental design for a tray for a drill press, as shown and described.
